UNITED STATES PATENT OFFICE.

HEINRICH LÖWY, OF GOTTINGEN, GERMANY.

METHOD FOR ASCERTAINING THE NATURE OF SUBTERRANEAN STRATA.

1,092,065.

Specification of Letters Patent. Patented Mar. 31, 1914.

Application filed April 1, 1913. Serial No. 758,262.

To all whom it may concern:

Be it known that I, Dr. HEINRICH LÖWY, a subject of the Austro-Hungarian Emperor, residing at 5 Buhlstrasse, Gottingen, Germany, have invented certain new and useful Improvements in Methods for Ascertaining the Nature of Subterranean Strata; and I do hereby declare the following to be a full, clear, and exact description of the invention, such as will enable others skilled in the art to which it appertains to make and use the same.

My invention refers to a method for investigating strata in the vicinity of mines.

I have found by experiment that the capacity and the damping coefficient of an antenna placed in a mine in the interior of the earth and energized by electrical oscillations is considerably influenced by the properties of the strata which surround the point where the antenna is located.

My invention consists in a method for ascertaining the nature of such strata by observing the behavior of such transmitters of electric waves.

To reduce my method to practice I determine the normal capacity and the damping coefficient of an antenna adapted to radiate electric waves, viz., when the antenna is surrounded by air or other substantially constant medium, and then determine the changes or variations of the capacity and the damping coefficient thereof when the antenna is located in different parts of a mine. By comparing the results of such measurements I can arrive at definite conclusions relating to the nature of the surrounding strata. Thus a stratum composed of clay (whose dielectrical constant is 13) interposed in strata consisting of salt (whose dielectrical constant is 6) is revealed by a considerable increase of the capacity of the oscillatory system (confer *Annalen der Physik* 36, 1911, p. 125). Instead of observing the capacity it is also sufficient to determine the frequency by means of a wave detector. Likewise the proximity of water and strata containing water can be discovered by the described means, and this is of specific usefulness in salt mines in which it is of the utmost importance to avoid striking such strata.

The accompanying drawing illustrates the mode of proceeding according to my present invention where the object is to investigate the nature of strata situated in the direction in which a gallery is to be driven.

Figure 1 is a plan section through a gallery showing diagrammatically apparatus placed in position for applying my method and Fig. 2 is a similar plan section with the apparatus placed in a position referring to a subsequent stage of the procedure.

At the end of a gallery G is placed a symmetrical antenna, consisting of two wires A₁, A₁ and A₂, A₂ stretched out horizontally along the bottom of the gallery. By determining the capacity and the damping coefficient of this system the nature of the rocks on both sides of the gallery is revealed. If the measurement shows that this portion of the surrounding strata does not contain any water, two bore holes B₁ and B₂, Fig. 2 are driven sidewise, thus making room for a crosswise spread of the antenna. The antenna A, A is then placed along the bore hole B₁, B₂ and by repeating the same measurements the nature of the rock situated in the direction of advance of the gallery is ascertained.

The longer the antennæ are made the larger is the range investigated and the smaller the number of measurements required. (Confer *Flemming Principles of Electric Wave Telegraphy* p. 551 and 552.)

Having thus described my invention what I claim is:

A method for ascertaining the nature of subterranean strata which comprises placing a preliminarily calibrated circuit capable of electric oscillations in a mine or bore hole and determining the variation of its capacity or its frequency and damping coefficient as compared with the prior calibration.

In testimony whereof I have affixed my signature, in presence of two witnesses.

DR. HEINRICH LÖWY.
